UNITED STATES PATENT OFFICE.

WILLIAM NERACHER, OF CLEVELAND, OHIO.

AUTOMATIC FIRE-EXTINGUISHER.

SPECIFICATION forming part of Letters Patent No. 361,179, dated April 12, 1887.

Application filed March 3, 1886. Serial No. 193,851. (No model.)

To all whom it may concern:

Be it known that I, WILLIAM NERACHER, of Cleveland, in the county of Cuyahoga and State of Ohio, have invented a new and useful 5 Improvement in Automatic Fire-Extinguishers; and I do hereby declare that the following is a full, clear, and exact description of the same.

My invention relates to automatic fire-sprinkling apparatus; and it consists of improvements in the distributing-valve and of improvements in the mechanism for holding and releasing the distributor-valve, all as hereinafter particularly set forth.

15 In the accompanying drawings, Figure 1 shows the mechanism partly in side elevation and partly in section. Fig. 2 shows a face view of the distributor-valve. Fig. 3 shows a vertical transverse section of the valve on line 20 xx of Fig. 2, the section of said valve shown in Fig. 1 being upon line yy of Fig. 2. Figs. 5 and 4 are vertical transverse sections of the link, formed of two parts, and connected by easily-fusible solder. Fig. 6 is a modified form 25 of the valve-center. Fig. 7 is a like view to Fig. 1, with the parts free as they appear in action. Fig. 8 is a section on the line zz of Fig. 1. Fig. 9 is a modified form of link.

The frame A is substantially the same as 30 that shown in Letters Patent of the United States granted to me on the 22d of April, 1884, No. 297,432. Into its neck 2 is screwed the coupling 1, which connects it with the pipe and forms the discharge-orifice thereof. This 35 coupling extends through the neck, and the lower end of it, a , forms the seat upon which the distributor-valve 3 is seated to close the discharge-pipe. The general form of the distributor-valve is the same as that shown in my 40 aforesaid patent. It has a smooth annular space about the central part fitted to the seat, between which and the seat may be interposed a thin copper washer, b . The edge of the distributor-valve is serrated or formed with salients, by means of which the water is distributed 45 more effectually, as explained in my aforesaid patent, and when the valve is in place it is held by the sides of the frame A fitting into the notches between these salients, so that when

the valve is released it can drop upon studs 50 13, by which it is held directly under the discharge-opening. The valve is formed with inwardly-turned spurs 16 and 17, for cutting up and spraying the water rebounding from the face of the distributor-valve.

55 Instead of the central core shown in my previous patents, I provide in the central part of the valve an annular serrated flange, 8, by which the central part of the stream of water is cut up and sprayed. This central part may 60 consist of a single annular flange, or of several, the inner being higher, forming a conical center; or the whole central cone may be solid, with the serrations over its entire surface, as shown in Fig. 6. In the center of the space 65 inclosed by this flange I may set a small post having a rounded or pointed top, as shown at 14, to further disperse the water. The valve and distributor are supported upon an intermediate post, 7, which has a rounded top bearing 70 against a socket on the under side of the valve, as heretofore shown by me; but the means for supporting the post and throwing it aside out of the way of the valve and distributor when the water is turned on are new.

75 A bell-crank lever, 5, is pivoted at one end of one arm at 11 in the frame, a little to one side of the center, and it has a spur, 18, directly opposite to the pivoted arm of the bell-crank lever, adapted to bear in the notched 80 lower end of the post 7. Preferably, this bearing of the spur in the notched end is a little out of line from the center of the upper bearing-point of the post, and the pivot of the bell-crank lever below this notched bearing-point 85 being on the side of the longer arm of the bell-crank lever, as hereinafter explained. This longer arm of the bell-crank lever is made, preferably, of elastic brass or steel wire, as at 6, bent to form two prongs, which are fixed in 90 the end of the horizontal arm or arms of the bell-crank lever 5. The post 7 is inserted in place under the valve, while the arm 6 is lowered, and when this arm is raised the lever and the post 7 act as a toggle-joint and force 95 the valve to its seat and hold it securely in place. The arm is held up by a link, D. This is composed of two parts, c d . These parts

are joined by slipping the legs of the upper part over the outside of those of the lower part, the legs of the upper part being spread and the legs of the lower part being correspondingly contracted, so that the lower part wedges into the upper part. The two parts are connected by easily-fusible solder between the lapping portions.

Fig. 4 shows the link with the parts united, 10 and Fig. 5 with the lower part dropping away from the upper; and from the latter figure it will be understood that as soon as the solder begins to melt, the upper part being held and pressure put upon the lower part to draw it 15 down, the lapping parts will not slide upon each other, but the lower will be drawn away from the upper, and thus will be released more promptly. This link is supported, in the manner shown, on the arm 4, cast with or secured 20 to the frame A. The lower end of the link sustains the arm 6. The link is put in place under some strain, caused by the elasticity of the arm 6, the parts being adjusted so that the arm 6 must be sprung slightly upward after 25 the distributor-valve is forced to its seat and before the link D can be slipped into place. On the frame I set stop-pins 12, to limit the upward movement of the arm 6. When it is released, its weight swings the bell-crank 30 lever on its pivot 11, throws aside the post 7, and allows the distributor-valve to drop freely. As these valves may remain in place a long time before any accidental fire causes 35 their removal, and as the water contained therein always contains more or less of elements of oxidation, the valves are liable to become rusted to their seats, so as not to be removable by the pressure of water, and therefore to fail in action at the proper time.

40 In order to prevent this, and also to form a secure joint, I have provided a seal of some substance, such as wax, (indicated in Fig. 1 at 15,) which may be melted and poured or otherwise forced into place between the distributor 45 or sprinkler valve and its seat, in order to exclude the water from the parts in contact and to prevent any oxidation. While I prefer wax or paraffine for this purpose, I do not confine myself to these, as there are many 50 equivalents well known. The wax or paraffine may be interposed between the upper surface of the distributor-valve and the thin copper washer b, which bears directly in the valve-seat; or it may be applied in any convenient way to form a water-tight joint about 55 the distributor-valve, in order to exclude the water from contact with the joint between the valve and its seat. The wax or paraffine will melt by the heat, which will release the fusible link, and will thus lubricate the parts which it previously served to cover.

In Fig. 7 I have shown a modified form of the connecting-link. In this figure, instead of the two parts of bent metal, one part may be made solid of approximately wedge shape,

with ledges a' for the support of the arm 6. The other part of the link may be made V-shaped, so that it may fit the wedge part b', to which it is secured by the fusible solder, the part c' of the link having an eye adapted 70 to fit over the arm 4.

The distributor may be used in an inverted position whenever desired, and, in order that the water may be directed to the portion of the room directly above the place where the 75 distributor is secured, I have formed openings in the upper rim of the valve, as shown at 19, with the side walls of said openings formed on an angle, so that the water will be deflected in all directions immediately above 80 the valve.

I am aware that prior to my invention it had been proposed to use two hollow conical sleeves, one connected to the shank of the valve and the other mounted on the frame, 85 held together by fusible solder, the pressure upon the valve being adapted to separate the cones when the solder is melted by heat. Further, I am aware that it is not new to secure a disk within a pipe by fusible solder and 90 place a core of fusible material in front of the same, so as to protect the disk from contact with the water, and I do not broadly claim such as my invention.

I claim as my invention—

1. A distributing-valve combined with the seat on the end of the discharge-pipe and a frame attached to the end of the discharge-pipe in which the distributor-valve may fall, 95 said valve having a central part provided with 100 projections of varying heights to disperse the water, substantially as described.

2. A distributing-valve combined with the seat on the end of the discharge-pipe and a frame attached to the end of the discharge-pipe in which the distributor-valve may fall, 105 said valve having a central post, 14, and a serrated flange, 8, surrounding said post, but of a less height, substantially as described.

3. In a fire-extinguisher, the discharge-pipe 110 and frame connected thereto, a valve supported within said frame, a bell-crank lever having one arm supported upon the frame and the other extending laterally at right angles thereto, in combination with a post intermediate between the bell-crank lever and the valve, and an easily-fusible link connecting the lateral arm to the frame, substantially as described.

4. In combination with a distributor-valve, 115 the discharge-pipe, the frame on the discharge-pipe containing the valve, the intermediate post, and the bell-crank lever having a short vertical arm, 18, and the supporting-arm 6, 120 extending laterally therefrom and at right angles thereto, and the easily-fusible link connecting said arm with the arm 4, substantially as described.

5. The combination, with a distributor-valve 125 having suitable supporting mechanism, of in- 130

dependent metal link adapted to place the parts under tension and to hold them in place, said link being composed of an upper part having diverging legs, a lower part having contracted legs, the two parts being held together by easily-fusible solder, substantially as described.

In testimony whereof I have signed my name to this specification in the presence of two subscribing witnesses.

WILLIAM NERACHER.
